UNITED STATES PATENT OFFICE.

MAURICE P. WHITNEY, OF ELMIRA, NEW YORK, ASSIGNOR TO ECLIPSE MACHINE COMPANY, OF ELMIRA, NEW YORK, A CORPORATION OF NEW YORK.

ENGINE-STARTER.

1,392,995.

Specification of Letters Patent. Patented Oct. 11, 1921.

Application filed October 13, 1919. Serial No. 330,218.

To all whom it may concern:

Be it known that I, MAURICE P. WHITNEY, a citizen of the United States, residing at Elmira, in the county of Chemung and State 5 of New York, have invented certain new and useful Improvements in Engine-Starters, of which the following is a specification.

My invention relates to an engine starter employed for the purpose of starting an 10 engine, such as an internal combustion engine and the same represents an improvement upon the type and construction of engine starter described and claimed in an application filed by William L. McGrath on 15 October 1, 1919, Serial No. 327,754, for improvements in engine starters. This type of starter is characterized by the embodiment of certain features of the Eclipse-Bendix drive but capable of operation by 20 manual or foot actuation for the engagement of the driving member or pinion with the engine member or flywheel of the engine, such engagement or meshing by means of the manual or foot actuation being either partial 25 or complete as desired.

The object of my invention is to provide the manual or foot operating mechanism with means whereby the starter may be operated in either direction by the full cycle 30 of movement of the manual or foot device at the comparatively slow speed of operation by hand or foot, but shall be disabled or disconnected at that speed of operation resulting from driving by power. This object is accomplished by means of a speed 35 control means coöoperating with said manual or foot operated mechanism which means forms an operating connection with the engine starter at all times except when such 40 starter is power driven, whereupon such means is disconnected or disabled.

In the drawings Figure 1 is a sectional elevation of a starter embodying my invention and Fig. 2 a cross section on the line 45 2—2 of Fig. 1.

The structure illustrated in the drawing is selected as one embodiment of my invention but it will be understood that such embodiment, as well as the character and construction of the engine starter itself, may 50 partake of different forms without departing from the spirit and scope of my invention.

Referring to the particular construction 55 herein shown, the prime mover is an electric

motor 1 having an extended armature shaft 2 extending through the end plate 3 of the motor frame and having an outer bearing at 4 in the outer end of a housing 5 which is attached by screws 6 to a bracket 7. This 60 bracket is in the present instance a part of the frame of the automobile engine whose flywheel 8 is exposed to the drive for starting purposes. The armature shaft which is the drive shaft of the drive or transmission 65 also has an intermediate bearing 9 formed in the extended outer end of a bracket 10 projecting from the end plate 3 of the motor. This bearing 9 supports the enlarged portion 11 of the driving shaft 2, which portion 70 forms a stop for the pinion as hereinafter described.

Upon the intermediate portion of the drive shaft is mounted a screw shaft 12 which has at its outer end a driven head 13. Upon this 75 screw threaded portion of the shaft there is screw threaded the driving member which is here in the form of a pinion 14, adapted to mesh with the gear of the flywheel 8.

The driven head 13 of the screw shaft is 80 operatively connected with a driving head 15 through the medium of a coiled drive spring 16 whose opposite ends are anchored to such heads respectively by studs 17 and 18. The screw shaft and its head 13 are not secured to 85 the driving shaft 2 but float thereon. But the driving head 15 is secured to or is a part of such driving shaft so that its motion may be communicated thereto and also the motion or rotation of the shaft 2 may be 90 communicated to such head 15.

Upon the driving shaft there is loosely mounted the rather long pinion 19 and to the outer end of such shaft there is secured a casing 20 having its central portion adapted 95 to receive and partially overhang this pinion 19. This casing is provided with a plurality of radial chambers 21 of two different counter bores, the outer being of the larger diameter. Within these chambers there are 100 located a series of plungers 22 having enlarged heads 23 such heads being loosely movable within the outer counter bore and the plungers proper being loosely reciprocal in the inner end of these chambers. These 105 plungers are retained within the casing by means of the circular band 24 secured to such casing by the screws 25. The inner ends of these plungers are adapted to coöperate with and engage the teeth of the pinion 19. When 110

the pinion is at rest or when the same is being operated at slow speed as by hand or foot operation, one of these plungers and preferably three thereof, as shown in Fig. 2, 5 are in operative engagement with the pinion by reason of gravity whereas the remaining three are free thereof.

The pinion 19 is adapted to be rotated in either direction by means of the depressible 10 plunger 26 which has a rack portion 27 on one side and which is normally held in its upper position by means of the coil spring 28. The lower end of this plunger is adapted to contact and operate the movable ele- 15 ment 29 of a switch 30 which supplies current to the motor 1. By preference the parts are so constructed and arranged that the pinion 14 is partially meshed with the flywheel by the hand operation before the 20 switch is operated after which full mesh is obtained in automatic manner by the rotation of the motor.

Describing a cycle of operation, when it is desired to start the engine the plunger 26 25 is depressed whereupon the pinion 19 is rotated. Inasmuch as this rotation is at a rather slow speed the plungers 22 will form the operative connection between this pinion and the shaft 2, with the result that such 30 shaft will be rotated and the pinion 14 will be advanced into partial mesh with the flywheel. The motor is now operated by the closing of the switch 30 and the pinion will thereupon be advanced into full mesh and 35 when stopped against the head 11 it will rotate and thereby rotate the flywheel and start the engine. When the engine has started on its own power the pinion 14 will be automatically demeshed and returned to normal 40 position. When the drive shaft and consequently the casing 20 is rotated at high speed by means of the motor 1 the plungers 22 will be thrown outwardly away from the pinion 19 by centrifugal force and 45 thereby cause a disconnection between such casing and this pinion. The plunger 26 is now free to rise, during which operation the pinion 19 will be rotated idly on the shaft 2.

The construction of my speed control 50 means is such that it is in operative engagement with the pinion 19 when at rest and also when such pinion and shaft 2 are rotated at such slow speeds as occur in manual or foot operation. And moreover, such engagement exists in both directions of rotation of such shaft. This latter is a feature of importance inasmuch as it permits of repetition of the initial movements to cause 55 partial meshing of the pinion 14 such as is required in the event that the teeth of the pinion 14 should abut end to end with the teeth on the flywheel. By repetition of the initial movements the pinion can be eventually properly meshed with the flywheel, but 65 for such movements it is necessary that the

pinion 14 should be restored to normal position and this requires a backward rotation of the shaft 2 and consequently the screw sleeve 12. This is accomplished by reason of the fact that the speed control means is 70 in constant operative connection with the pinion 19 during these preliminary movements, that is, both in the downward and upward movements or strokes of the plunger 26. Consequently after this plunger has 75 been depressed and in case the pinion 14 should abut against the flywheel teeth, the operator releases the pressure on the plunger 26 and permits it to rise whereupon the parts including pinion 19, casing 20, shaft 80 2 and shaft 12 are rotated in the opposite direction, with the result that the pinion 14 will be retracted to normal position and made ready for the repetition or next preliminary starting movement.

I claim:

1. The combination of a motor driven rotatable shaft, a driving member mounted thereon for automatic longitudinal movement thereof and for rotary movement therewith, and manually operated mechanism for rotating such shaft, such mechanism including speed controlled means for disabling such mechanism upon excessive speed rotation of the shaft.

2. The combination of a motor driven rotatable shaft, a driving member mounted thereon for automatic longitudinal movement thereof and for rotary movement therewith, and manually operated mechanism for rotating such shaft, such mechanism including a clutch adapted to be disabled upon excessive speed rotation of the shaft.

3. The combination of a motor driven rotatable shaft, a driving member mounted thereon for automatic longitudinal movement thereof and for rotary movement therewith, and manually operated mechanism for rotating such shaft, such mechanism including a clutch operative at manual driving speeds of the shaft but inoperative at power driving speeds thereof.

4. The combination of a motor driven rotatable shaft, a driving member mounted thereon for automatic longitudinal movement thereof and for rotary movement therewith, and manually operated mechanism for rotating such shaft, such mechanism including a manually operated rack, a pinion mounted on the shaft and driven by the rack and a speed controlled connecting means between the pinion and shaft adapted to operatively connect such parts in both directions of rotation of the shaft.

5. The combination of a motor driven rotatable shaft, a driving member mounted thereon for automatic longitudinal movement thereof and for rotary movement therewith, and manually operated mechanism for

- rotating such shaft, such mechanism including a manually operated rack, a pinion mounted on the shaft and driven by the rack, and speed controlled means comprising a plurality of radially movable plungers operatively connected with the shaft, some of which plungers constantly engage the pinion when at rest and when rotated at a manual driving speed but which are rendered inoperative at a power driving speed. 5
6. The combination of a motor driven rotatable shaft, a driving member mounted thereon for automatic longitudinal movement thereof and for rotary movement therewith, and manually operated mechanism for rotating such shaft, such mechanism including a manually operated rack, a pinion mounted on the shaft and driven by the rack, and speed controlled means comprising a casing secured to the shaft, a plurality of plungers mounted therein radially with respect to the shaft and pinion and in position so that one or more thereof constantly engage the pinion when at rest and when rotated at a manual driving speed but adapted to be disengaged therefrom by centrifugal force when rotated at a power driving speed, said plungers having weighted heads. 10

8. The combination of a motor driven rotatable shaft, a driving member mounted thereon for automatic longitudinal movement thereof and for rotary movement therewith, and manually operated mechanism for rotating such shaft, such mechanism including a manually operated rack, a pinion mounted on the shaft and driven by the rack, a casing secured to the shaft and having a central bore overhanging a portion of the pinion and a plurality of plungers arranged radially in the casing and around the pinion and adapted to reciprocate within such casing and into contact with the pinion. 45
9. The combination of a motor driven rotatable shaft, a driving member mounted thereon for automatic longitudinal movement thereof and for rotary movement therewith, and manually operated mechanism for rotating such shaft, such mechanism including a clutch operatively connected with the drive shaft in both directions of rotation thereof, such clutch being speed controlled but affected only by the high speed of the shaft when driven by the motor. 55
